UNITED STATES PATENT OFFICE.

ANDREW J. CARMICHAEL, OF NEW HAVEN, CONNECTICUT, ASSIGNOR TO THE GREIST MANUFACTURING COMPANY, OF NEW HAVEN, CONNECTICUT, A CORPORATION OF CONNECTICUT.

PORTABLE LAMP BASE.

Application filed April 17, 1923. Serial No. 632,740.

This invention relates to bases for portable lamps.

The type of portable lamp base to which the present improvements relate more particularly, is hollow and has concealed therein a spiral clamping device for holding the base to a support such as a table. An important feature of the present invention is found in a conical shaped sheet metal member which is located within the outer, conical shaped, thin sheet metal base shell to which latter it conforms in contour. The inner sheet metal member of the base is provided with means for fastening thereto the inner end portion of the coil spring which is housed within the base when out of use. The major portion of the coil spring, including its outer or free end, is of such extent as to pull out from the base a distance sufficient to pass over a bed post, the edge of a table or other support of considerable thickness. This is due to the fact that the spring clamping member is attached at its inner end to the inner base supporting member, leaving free sufficient extent of the spring to embrace supports of greater thickness than would be the case, for example, if the spring was fastened to the base at a point intermediate the two ends of the spring. In this connection, an important feature of the invention is comprised in the means for securing the clamping member to the inner base support, which consists in punching or forcing loops from the body of said support, passing the end of the spring through said loops, and then closing the loops tightly against the spring end to attach it to the base.

Another important feature of the invention is comprised in a coil clamping member which is secured within the base of the lamp at points near the inner end of said member, said member comprising a simple spiral which is located in substantially a single plane when housed within the base, and requires no other support.

Another important feature of the invention is comprised in a disc washer which is clamped by the over-turned portions of the end of the lamp stem in position against the inside of the base of the lamp, and at a point intermediate the extremities thereof. This arrangement gives greater strength to the base than would be the case if said washer

were clamped close up in the conical end of the base at the point where the lamp stem enters. It also adds stability to the base as a whole, as compared with other constructions.

Other features of the invention, including important details of construction, and combinations of parts, will be more particularly described hereinafter and the novel features pointed out in the appended claims.

In the accompanying drawings:

Fig. 1 represents a lamp base, embodying the features of the present invention, in side elevation:

Fig. 2 is an inverted plan view, and,

Fig. 3 is a vertical section on the line 3—3, Fig. 2, showing the base clamped to a support.

The numeral 3 indicates the outer, thin metal shell of the base which as shown is conical in form and may be provided at its lower outwardly flared edge with an inwardly rolled portion 2. Internally of the thin metal shell 3 is a stiffening and stabilizing base frame member 5. This member is made of sheet metal of considerably greater thickness than the outer shell 3. As a convenient and economical mode of manufacturing the frame member 5 the same is formed originally from a disc-shaped blank from which, at four equi-distant points, V-shaped slots 16 are cut out. Subsequently, the blank is formed into conical shape to follow the configuration of the shell 3, the bending of the blank into such shape causing the V shaped slots to close so as to present, at points 90° apart in the frame member, slots 16. This method of manufacture permits shaping of the frame member by dies, or otherwise, without distortion of the metal; and prevents fracture during manufacture.

The upper conical ends of the shell 3 and frame 5 are provided with a hole to receive the hollow stem 50 of the lamp, said stem being provided with a bead or shoulder 6 which supports the stem against the shell 3. The outer extremity of the stem 50 has a hinge joint by which it is connected with the lamp or lamp socket 9. A washer 11 formed of suitable thickness is located within the shell 5 and is of a size just sufficient to rest against the inner surface of the shell at a point substantially midway of the base. This washer is provided with a central per-

foration through which extends the end of the stem 50, said end being formed with tongues 13 which are bent over upon the face of the washer, the washer being thus 5 clamped firmly against the inside face of the member 5. It will be seen that as the annular shoulder 6 bears rigidly against the margin of the hole in the shell 3 through which the stem passes, when the tongues 13 10 are turned over upon the washer 11 the stem 50, shell 3, and base 5, will be tightly clamped together by the pressure exerted through the washer 11. The location of this washer imparts strength and rigidity 15 to the base, and to a greater extent than would be the case if the washer were clamped close up within the conical end portion of the frame, where the stem 50 enters. The construction also provides a bearing 20 over which to rivet or fold two or more projections as 13 from the lower end of the lamp stem at a point located well down within the base of the lamp, thus providing greater increased strength and stability in the device 25 by which the lamp stem is attached to the base as compared to the strength that would be imparted by the lower projections of the stem if the same were riveted or formed over close up under the conical end of the 30 base shell, or the sheet metal supporting member 5 thereof.

Internally of the shell member 5, at suitably spaced points, pairs of parallel slits are formed transversely of the shell, and the 35 metal between said slits is forced or punched inwardly to form loops 17. These loops receive the inner end portion of the spiral spring clamping member 15, said member being preferably formed of wire, suitably 40 tempered to impart resiliency thereto. The clamp 15 has any desired number of coils and it is free from its point or points of attachment 17 outwardly to its extreme end. Said coils normally lie housed within the 45 hollow base as shown in Fig. 2, but the outer portion of the clamp may be pulled from within the base and located over a table, bed post, or any suitable support B for clamping the lamp base thereto. When removed from the support B the clamp 15 will 50 automatically be drawn within the base, and will lie in substantially a single plane. To prevent marring the surface of the furniture with which the clamp comes into contact a suitable portion thereof is incased in 55 a rubber covering 18, or the like.

Changes may be made in the details of construction, or in the particular arrangement of the parts described without departing from the spirit of the invention, and the right is reserved to make such changes as are within the scope of the following claims.

Having thus described my invention what I claim as new, and desire to secure by Letters Patent of the United States is:

1. A lamp base comprising an outer sheet metal member, an inner shell of heavier metal than the first-named member but shaped to conform substantially to the latter, a stem extending centrally through said members, and a washer separate from, but bearing at its periphery against the interior of said shell, said stem extending through said washer and having its end secured thereto. 75

2. A lamp base comprising an outer thin metal shell of conical form, an inner shell of heavier material substantially conforming in shape to the outer shell, a rigid metal washer located within the base and bearing at its outer edge against said inner shell at a point substantially midway of the ends of said shell, and a stem passing through apertures in said shells and having its inner end passed through a central aperture in said washer, and means formed from the metal of said stem for rigidly securing the stem to the washer, whereby the stem, washer and two shells are clamped together. 80 85

3. A lamp base comprising an outer thin metal shell of conical form, an inner shell of heavier sheet metal conforming substantially to the shape of the outer shell, said shells provided at their apices with registering holes, a washer of rigid material located within the inner shell and having its outer edge bearing on said shell at a point substantially midway the ends of said shell, said washer having a central aperture, and a lamp stem extending through the apertures in said shells and washer, said stem having an annular stop bearing upon the outer shell about the opening therein, and having at its inner extremity tongues which are bent over upon the inner face of said washer, whereby said parts are rigidly clamped together. 95 100 105

4. A lamp base comprising an outer thin metal shell of conical shape, an inner shell of heavier sheet metal than said outer shell, said inner shell having spaced radial slots, 110 extending from the outer periphery of the shell inwardly and terminating near the top thereof, said slots being spaced approximately 90° apart, said shells having aligned perforations at their apices, a lamp stem passing through said perforations, a disk located midway of said inner shell and provided with a central perforation, the inner end of said lamp stem passing through said perforation and means at the end of said stem for engaging the under surface of the disk, whereby said stem, disk and inner and outer shells are clamped together. 115 120 125

5. A lamp base comprising an outer conical shell of sheet metal, an inner conical shell of heavier sheet metal than said outer shell and fitting the inner surface of the latter, said inner shell imparting sufficient stability and rigidity to the outer shell to maintain said base in position on a stand, said inner 130

and outer shells having aligned perforations at their apices, a stem extending through said perforations, and a rigid washer located within the inner shell and engaged at its outer edge with said shell at a point midway of the latter, said washer provided with a central perforation to receive the end of

said stem, and means formed from the metal of said stem and upset upon the inner face of said washer to hold said parts together. 10

In testimony whereof I have hereunto set my hand this 7th day of April A. D. 1923.

ANDREW J. CARMICHAEL.
